COMBINED SNAP SWITCH FOR
FLASH LIGHTS

Clarence E. Pryor, Elizabeth, N. J.

Application October 23, 1931, Serial No. 570,606

4 Claims. (Cl. 240—10.66)

My invention relates to switches for electric flashlights and like electrical devices.

Particular features of the invention reside in simplification of the individual structural parts and assembly of the same and of the snap switch for making and breaking the circuit through the lamp bulb; the utilization as a structural part of the switch of a resilient member cooperating to adjust the effective focus of the light rays emitted by the electric bulb and reflected by the reflector; utilization of a structural part of the switch in association with the metal exposed cap end portion of the flashlight casing for testing the integrity of electrical lamp bulbs, fuses, etc.; utilization of a structural part of the switch in association with a suspension member as in the form of a ring or open hook or the like for the testing of electrical devices having a length greater than is afforded by testing with the metal exposed cap end portion of the casing, and other features as will appear more fully hereinafter.

My switch structure is applicable with or without the use of a suspending ring for the flashlight. Such suspending ring, when desired, may form a combinational part with my switch, particularly when the ring is designed for use in the testing of fuse plugs and other electrical devices, the dimensional requirements of which exceed that afforded by the spacial distance between the metal exposed portion of a structural element of the switch and the metal exposed cap end portion of the casing.

In certain forms of my invention, wherein a suspending ring or other suspending device is not employed, and therefore does not form a structural part of my switch, my invention provides a switch structure which embodies a resilient member serving to function in the adjustment of the focus of the light rays. This form of my invention is applicable for the testing of electrical devices.

My invention may also embody an open hook member for the suspension of the flashlight, the open hook affording definite advantages over the usual closed ring. Provision is also made for the retention of the hook in its nonsuspending position substantially flush with the configuration of the casing, and preferably biasly retained in its non-suspending position.

My invention is further applicable to the association of the hook suspending member as a structural element of my switch, to afford in association with my electrical switch the testing of electrical devices.

Further features and objects of the invention

will be more fully understood from the following detail description and the accompanying drawings, in which

Fig. 1 is a side elevation of an embodiment of my invention inclusive of a suspending ring; the view in this figure is broken away toward the left hand end, and is also shown in central vertical sectional elevation at the right hand end, to reveal otherwise hidden parts;

Fig. 2 is a sectional elevation on line 2—2 of Fig. 1, on a slightly enlarged scale;

Fig. 3 is a sectional elevation on line 3—3 of Fig. 2; this view also illustrates the utilization of my invention with the suspending ring for the testing of the integrity of an electrical fuse;

Fig. 4 is a top plan view of Fig. 3, the parts having been rotated through an arc of one hundred and eighty angular degrees;

Fig. 5 is an explosive view showing detail parts;

Fig. 6 is a side elevation similar to Fig. 1 of another embodiment of my invention;

Fig. 7 is a sectional elevation on line 7—7 of Fig. 6;

Fig. 8 is a sectional vertical elevation on line 8—8 of Fig. 6;

Fig. 9 is an end view of a further embodiment; and

Fig. 10 is a central vertical sectional elevation on line 10—10 of Fig. 9.

Fig. 11 is an explosive view of detail parts.

Fig. 12 is a perspective view of a further embodiment of my switch element and its mounting means.

The casing of the flashlight is illustrated in the drawings of circular cross-sectional configuration, but may be of any desired configuration.

Within the casing 10, I have illustrated the usual one or more electrical dry cells 11; each such cell, pursuant to present practice, is formed of an outer casing of zinc serving as the anode, the bottom 12 of the zinc casing being exposed and the side insulated by a sleeve of paper or equivalent, the central electrode 13, usually of carbon, serving as cathode, projecting sufficiently to contact either with the bottom of an adjacent cell or with the terminal 14 of the electric lamp bulb 15. Usually such lamp bulb is provided with a spiral sleeve for meshing with the corresponding spiral threading 16 of the socket 17. The reflector 18 is integral with or secured to the sleeve 17, by its hollow hub 19. The reflector and the above stated associated parts and the lens 20 are retained in position by the front end cap 21, which is usually formed of two mutually threaded sleeves, as appears in Fig. 1.

Usually, the central portion 10a of the metal casing 10 is covered with lacquer or other electrically insulating material, serving the purposes of ornamentation as well as protection of the exposed metal against corrosion and indication of wear.

The front end cap members are usually metal exposed and nickelized or otherwise protected from corrosion, and similarly the rear end cap 22. The 10 rear end cap 22 is similarly provided with or formed with threading for meshing with the threading 10b of the metal casing 10, for the purpose of securement of the end cap, and also, with or without cooperation with the threaded 15 front end cap, for the adjustment of the focus of the light rays emitted by the lamp bulb and reflected by the lens 20.

As above indicated, a feature of the embodiment illustrated in Fig. 1, is the dual function 20 of my snap switch assembly for the adjustment of the focus of the light rays.

One form of my switch, preferably of the snap type, is illustrated in Figs. 1 to 5; this embodiment of my invention is also applicable for the 25 testing of electrical devices.

As is illustrated in Figs. 1 to 3, my snap switch comprises the manipulative member 23, which in the illustrated embodiment serves as the movable switch member; its end 24 projects exteriorly of the casing through the slot 125 in the end cap 22. In the form illustrated, see Figs. 1, 2, 3 and 5, the switch member is formed of a strip of resilient metal of good electrical conductivity and comprises in essence the body portion 23a, thereto connected angular portion 23b and the outermost angular portion 23c. In certain types of embodiments of my invention, the additional terminal portion 23d is also provided, serving as a limiting stop in the flexing of the angular portions 23b, 23c, as will appear more fully herein-after.

Associated with the switch member 23, I provide insulating and positioning disks, and as illustrated in Figs. 1 to 5, comprises the positioning 45 disk 25, provided with the slot 25a for the insertion therethrough of the angular portions 23b, 23c, and retention of the body portion 23a of the switch member 23; further, the positioning disk 26 which is provided with the radially open-ended recess 26a for the reception therein of the body portion 23a of the switch member 23; and the insulating disk 27 of fibre or other suitable electrically insulating material.

As appears from Figs. 1, 2 and 3, the assembly 55 of my switch member is as follows: the insulating disk 27 is positioned within and at the bottom of the rear end cap 22, the positioning disks 26, 25, being located in the order named, the switch member 23 having been threaded through the slot 25a of the disk 25, and its body portion 23a passed through the recess 26a of the disk 26, the free end 24 extending through the slot 125 in the end cap 22. The end cap 22 is then threaded upon the rear end of the casing 10, until the 65 portion 23c of the switch member 23 engages the bottom 12 of an electrical cell 11, whereby the switch member 23 is connected in the negative side of the electrical circuit.

In flashlight constructions embodying my invention, wherein the metal of the reflector 18 engages and makes electrical contact with the metal of the front end cap 21, the metal material of the casing and therewith the metal of the end caps is connected in the positive side of the electrical circuit, and accordingly suitable arrange-

ment is made for the movement of my switch member 23 into and out of contact with the metal of the rear end cap 22 for effecting the closure and opening of the circuit through the lamp bulb.

As one form of such arrangement, I provide the positioning disk 26 further with the depression 26b within the radial extension 26c, the extension 26c projecting through the slot 125 in the rear end cap 22 to locate the depression 26b and therewith the switch member 23 when moved into the depression 26b, to engage and make electrical contact with the metal of the rear end cap 22, for the circuit-closing position of the switch, that is to say, for the lighting of the lamp bulb.

I also provide the positioning disk 26 with the further radial extension 26d having therein the central depression 26e, for receiving and retaining the switch member 23 when moved therein, for its test position.

By the provision of the radial extensions 26b and 26d, positioned at opposite sides of the radially open recess 26a, there is provided the clearance 26f, see Fig. 5, which effects a functional operation with a suspension member such as the suspending ring, usually pivotally mounted on the rear end cap 22. One such pivotal mounting may be had by forming the pivot ears 29, the ends of the ring 30 being snapped therein.

As will appear from the above, the metal end 24 of the switch member 23 projects exteriorly of the casing, i. e., exteriorly of the rear end cap 22, and is connected in the negative side of the circuit whereas the casing and its end caps are connected in the positive side. Accordingly, to preclude shortcircuiting of the circuit in the event of simultaneous engagement of the end 24 of the switch member 23 and the casing 10 and/or either end cap with metallic material, I mount the button 28 of electrically insulating material on the end 24 of the switch member 23.

For testing electric lamps such as automobile lamps and other lamps of the so-called miniature and of the smaller socket types, the insulating button 28 is provided with a groove 28a extending to the circular perimeter of the button, sufficient length of the end 24 of the switch member 23 being provided to enable the end 24 to be downwardly turned within such groove. Preferably, I provide two such grooves 28a, and bisect the end 24, and bend one of such bisected ends 24a in a groove 28a positioned toward the front of the casing and the other end 24b in a groove 28a positioned toward the rear of the casing, see Fig. 3, such grooves 28a being of sufficient width to enable the electrical devices to be tested to be effectually received therein for the purpose. Thus for the testing of electrical devices of small size, such as a miniature electric bulb, the end 24 of the switch member is shifted to its neutral, locked position at 26e, and the bulb placed with its central contact engaging the metal of the rear end cap 22 and its shell received within a groove 28a to engage a bisected end 24a of the switch member 23. In the event its filament is integral, the lamp 15 of the flashlight is lighted, and in the event of non-integrality of its filament, the flashlight lamp 15 is not lighted.

In the forms of my invention utilizing a ring suspension member 30, such ring may have the dual purpose of cooperation with my switch, to effect lighting or non-lighting of the flashlight bulb 15 when the ring 30 is in its suspending position, or as an element in the testing of electrical devices.

For either or both such purposes, one end, see 150

30a, see Figs. 1, 2, 3 and 4, may be bent, so that such bend 30a engages the rear face of the switch member 23 when the member 23 is moved to enter the clearance 26f of the disk 26 and the ring 30 is in its closed position, as in Fig. 1, the insulation disk 27 being provided with the opening 27a to effect such electrical contact. In such form and status of parts, upon moving the switch element to the position 26f, the flash lamp 15 is lighted when the ring is in its non-suspending position, but upon moving the ring to its suspending position, it is now prepared for the testing of an electrical device such as a cartridge fuse, see 31, Fig. 3, by spanning the same to place one of its terminals 31a to engage the ring 30 and the other terminal 31b to engage a bisected end 24a or 24b in a groove 28a of the button 28.

To effect lighting of the flash lamp 15 with the ring 30 in its suspending position, the switch member 23 is moved into its locking notch 26b, whereat it engages the metal of the rear end cap 22.

In the above described forms of my invention, the disk 27 is preferably provided with a radial extension 27b to suitably locate the switch element 23 when positioned in the clearance 26f of the disk 26.

From the above, in addition to the features of closing and opening the circuit of the flashlight lamp, it will be observed that the regulation of the focus of the light rays emitted by the lamp bulb is attained by turning the rear end cap in the proper direction, and as illustrated, a right-hand screw turn adjusts the focus of the light rays more closely toward the lens and a left-hand screw turn adjusts the light focus more remotely. In the focal adjustment, the resilient parts 23b, 23c, of my switch element 23 function jointly in the axial displacement of the one or more electric cells and flexing of the combined lamp bulb and reflector assembly, pursuant to present practice, to shift the lamp bulb axially relative to the lens; at each stage of focal adjustment, the mechanical contact and electrical engagement of my switch member 23 is effectually maintained with the cell bottom 12. It will be further observed that the disc 27 of insulation material serves as the abutment for the switch member 23, in such adjustment.

In the construction illustrated in Figs. 6, 7 and 8, the switch is of simplified form, in that it embodies the primary features of the switch for the closing and opening of the circuit through the lamp bulb, and also affords testing of electrical devices.

The structural parts of the flashlight as a whole are largely similar to the parts embodied in the construction illustrated in Fig. 1, and like parts are designated by the same reference characters. However, with respect to the flashlight construction per se, I have illustrated the metal disc 33 toward the front end of the casing 10, against the rear face of which abuts the lamp socket 16, which disk 33 is flexed to more or less extent in the operation of adjustment of the light focus.

Also, my switch construction embodied in Figs. 6, 7 and 8 comprises but two discs, namely, the insulation disc 34 and the positioning disc 35. The disc 34, see Fig. 11, in such construction, is of electrically insulating material and comprises a flat circular body portion and a locking flange extension 34a; the latter is shown of the bayonet joint type, namely, a recess 34b for affording and maintaining contact between the end 24 of the switch element 23 with the metal of the rear end

casing 22 and the re-entrant recess 34c for locking the switch end 24 in its circuit opening position, a portion of the insulating flange 34a being thereby interposed between the switch element 23 and the metal of the rear end cap 22.

The disc 35 is provided with a radially extending recess 35a and a positioning slot 35b, through the latter of which the body portion of the switch element 23 is passed, to attain the pivotal mounting of the switch element 23; the clearance 35c affords a locked positioning of the end 24 of the switch member 23 when in its circuit-closing position.

The construction of my switch, as embodied in Figs. 6, 7, 8 and 11 is also applicable in conjunction with a suspension member, the suspension member as appears in Figs. 9 and 10 in this instance, being illustrated of an open hook type, in lieu of the closed ring illustrated in Figs. 1 to 5 hereinabove described.

The open hook 36 is mounted in any suitable manner, but preferably pivotally on the outer face of the bottom 37 of the rear end cap 22 in spaced bearings, conveniently afforded by forming and bending the spaced ears 38, 39 in the metal of the bottom 37.

Such hook 36 may be utilized as a suspension member solely, the open hook feature being particularly advantageous as compared with a closed ring or other closed suspension member, whereby the positioning and removal of the hook upon suitable suspending means, such as a cross bar under the hood of an automobile, or the like, is superior to that of a closed suspension member.

Desirably, the hook suspension member 36 is snapped in its non-operative position, as by forming the angularly related depressions 40, 41 in the rear face of the material of the bottom 37 of the rear end cap 22, the lateral edges of the depression 41 being arranged to hold the hook in its non-operative position by snap relationship with the open end of the hook, the flexibility of which is enhanced by its open construction.

If desired, the open hook suspension member may cooperate with my snap switch, which co-operation is illustrated as effected in a manner similar to the cooperation of a suspension ring 30, hereinabove described, and comprising a laterally bent terminal portion 36a corresponding to the bent portion 30a of the suspension ring 30.

The testing of electrical devices with my switch with the use of suspension hook 36, is similar to that hereinabove described relative to the suspension ring 30.

In the embodiment illustrated in Fig. 12, the mounting means for the switch element 23 has been simplified, namely, a single disk element 41 serving jointly as the circuit-position locking disk and the element retention disk. As illustrated in Fig. 12, the disk 41 is substantially parallelly slotted at locations toward its center, the intervening portion between the slits being offset to provide a raised tongue 42 through which the body portion of the switch member 23 is passed, a degree of friction being provided between the under face of the tongue 42 and the body of the switch element 23 to sufficiently retain the switch member within the tongue. The disk 41 is also provided at its perimeter with a circuit-locking flange extension 34a, the parts thereof corresponding generally to the parts of the disk 34 illustrated in Fig. 11, and accordingly like parts are designated by like reference characters. Preferably, one edge 42a of the tongue 42 is arcuate, the radius being located

in a direction toward the extension flange 34a, to facilitate the rocking or rotatable movement of the body of the switch member 23 in attaining its respective circuit-closing and circuit-opening positions.

It will be understood that insulation is provided for the respective disk mounting means for the switch member 23; in such instances of use where the end cap 22 is of metal; however, it will be apparent to those skilled in the art that the end cap may be made of non-conducting material, such as molded bakelite or other suitable moldable, electrically insulating material, and suitable provision is made for facially embedding and retaining a strip of metal, or equivalent, in the material of the end cap, as on the inner face of the end cap, such strip extending at its one end to engage the end 24 of the switch member 23 when it is in its circuit-closing position and at its opposite end to engage and make good electrical contact with the metal of the cylindrical body portion of the casing 10, or equivalent arrangement to effect electrical contact with the lamp mounting means and therewith close the circuit through the electric lamp, when the switch member 23 is in its circuit-closing position.

Whereas I have described my invention by specific reference to various forms thereof, it will be understood that many changes and modifications may be made without departing from the spirit of the invention.

I claim.

1. In an improved combined end cap and switch for a flashlight, the combination of a threaded end cap, of a make and break switch means including a pair of spaced fixed discs secured within the end cap, a slot in the side wall of the end cap, a rotatable contact member having one end extending laterally through the face of one of said pair of fixed discs and the other end extending radially of the end cap and through the slot, and terminating at a point without the end cap, a fixed disc positioned between the pair of fixed discs and provided with a radial slot acting as a housing for the radially extending end of the contact member, and pivoted means, carried by the end cap and movable at will to engage or disengage with the rotatable contact member.

2. In an improved combined end cap and switch for a flashlight the combination of a threaded end cap provided with a slot in the side wall and lying in a plane transverse to the axis of the cap, and with a pivotally mounted suspension ring normal-

ly lying in engagement with the rear or closed end of the cap, a switch operating projection on said suspension ring normally in switch operating position, a plurality of discs housed within the cap and provided with projections extending through the slot in the rear cap, a switch member housed within the plurality of discs and rotatable therein and having an arm extending laterally outward through the said slot in the side wall of the cap, said switch member being normally engaged by the suspension ring and means formed on one of the plurality of discs for holding the switch member in engagement with the end cap.

3. In an improved combined end cap and switch for a flashlight the combination of a threaded end cap provided with a slot in the side wall and lying in a plane transverse to the axis of the cap, and with a pivotally mounted suspension ring normally lying in engagement with the rear or closed end of the cap, a switch operating projection on said suspension ring normally in switch operating position, a plurality of discs housed within the cap and provided with projections extending through the slot in the rear cap, a switch member housed within the plurality of discs and rotatable therein and having an arm extending laterally outward through the said slot in the side wall of the cap, said switch member being normally engaged by the suspension ring and means formed on one of the plurality of discs for holding the switch member in engagement with the end cap and out of engagement with the suspension ring.

4. In an improved combined end cap and switch for a flashlight the combination of a threaded end cap provided with a slot in the side wall and lying in a plane transverse to the axis of the cap, and with a pivotally mounted suspension ring normally lying in engagement with the rear or closed end of the cap, a switch operating projection on said suspension ring normally in switch operating position, a plurality of discs housed within the cap and provided with projections extending through the slot in the rear cap, a switch member housed within the plurality of discs and rotatable therein and having an arm extending laterally outward through the said slot in the side wall of the cap, said switch member being normally engaged by the suspension ring and means formed on one of the plurality of discs for holding the switch member out of engagement with the end cap and suspension ring.
